UNITED STATES PATENT OFFICE

154,585

DESIGN FOR A STORE FRONT

Clifford Bell, Birmingham, Mich.

Application July 5, 1947, Serial No. 140,116

Term of patent 3½ years

(Cl. D13—1)

To all whom it may concern:

Be it known that I, Clifford Bell, a citizen of the United States, residing at Birmingham, in the county of Oakland and State of Michigan, have invented a new, original, and ornamental Design for a Store Front, for which the following is a specification, reference being had to the accompanying drawing, forming a part thereof, in which:

The side of the store front not shown is identical with the side thereof which is shown in Figure 3.

I claim:

The ornamental design for a store front, substantially as shown and described.

CLIFFORD BELL.
